DOOR FASTENER

Edward R. Sargent, New Haven, Conn., assignor
to Sargent & Company, New Haven, Conn., a
corporation of Connecticut

Application March 31, 1936, Serial No. 71,905

2 Claims. (Cl. 292—274)

This invention relates to safety door fasteners, and more particularly to a device designed to be secured to the door jamb and door stile at the opening edge of the door to limit the amount the door is permitted to open.

In order to prevent unauthorized intrusion into a room or house when a door is opened in response to the bell or knocker, it has been quite common to employ chain door fasteners to limit the amount which the door can be opened. Such a structure is usually in the form of a chain secured to the door jamb at one end and provided at the other end with a member slidably engaged with a slotted plate or fitting attached to the door, the chain thus spanning the opening edge of the door and by its length limiting the extent to which the door will be permitted to open. The end of the chain, which engages the fitting upon the door, can be readily disengaged from the fitting so that the door will be permitted to open to its full width when desired.

Such a structure has several disadvantages, one of which is that when the door is opened the chain engages and is drawn across the door's edge, and the result is that the finish is marred, and in some instances the edge is badly mutilated. Also, the length of the chain is often such that the door may be opened a sufficient extent to permit the entrance of the hand of an intruder to disengage the end of the chain from the fitting. Again, with a proper tool, such as a pair of pliers or the like which may be slipped through the opening, the chain may be cut.

One object of the present invention is to obviate the disadvantages of the chain door fastener above referred to and provide a door fastener without these disadvantages which will be efficient and serviceable in operation.

Another object of the invention is the provision of a door fastener which, while limiting the opening of the door, will not come into contact with the edge thereof so as to mar the door, and will not strike the door jamb when in disengaged position.

Another object of the invention is the provision of a door fastener which will be of ornate appearance, efficient and serviceable in operation, and which may not be disengaged or destroyed by an intruder.

A still further object of the invention is the provision of a safety door fastener having a solid bar member designed to be pivotally connected to the door jamb and slidably connected to the fitting applied to the door, and to extend across the opening edge of the door so as to limit the

extent of opening permitted and yet not come in contact with the edge of the door.

To these and other ends, the invention consists in the novel features and combinations of parts to be hereinafter described and claimed.

In the drawings:

Fig. 1 is a front elevational view of a door fastener embodying my invention;

Fig. 2 is a sectional view on line 2—2 of Fig. 1 and enlarged relatively to the disclosure of Fig. 1;

Fig. 3 is a view similar to Fig. 2 but showing the door at the limit of its open position as permitted by the door fastener;

Fig. 4 is a sectional view on line 4—4 of Fig. 2;

Fig. 5 is a side elevational view of the door fastener disengaged from the door; and

Fig. 6 is a front elevational view of the plate or fitting applied to the door.

To illustrate a preferred embodiment of my invention, I have shown in the drawings a portion of a door 10 designed to close in cooperation with the door frame or jamb 11. Upon the door is mounted a plate or fitting, shown in elevational view in Fig. 6. This fitting 12 is provided with a raised central portion 13 in which is a longitudinal slot 14 extending substantially throughout the length of the fitting and provided with enlarged and upwardly extending ends 15 and 16 whereby the slot is of generally U-shaped design. Above and below the raised portion 13, the fitting is provided with flat plane portions containing screw openings 17 to receive the screws 18 by which the fitting may be secured in place. Each of the ends 15 and 16 is provided with a latching step 15a and 16a, and the corners between the enlarged ends 15 and 16 of the slot 14 and the slot proper may be beveled off as shown at 19 for a purpose to be hereinafter described.

The door fastener comprises a plate 20 adapted to be secured to the door jamb 11 by screws 21. To this plate is pivoted a base member 22, this member being provided with a pin or stud 23 which is received rotatably in an opening in the plate 20 and riveted over a washer 25. It will thus be seen that the pin 23 will be rotatable with respect to the plate 20 about a horizontal axis, according to the usual manner of installing the device.

The base member 22 is provided with outwardly projecting ears 26 and 27, to which is pivoted by the pivot pin 28 the solid bar member 29.

It will be observed that this member 29 is of arcuate shape, although it may be made of relatively heavy material so as to be rigid and substantially inflexible.

The bar member 29 is provided upon its free end with a finger piece 30 which projects outwardly from the bar, and at the same end the bar is provided at its under side with a lug 31. This 5 lug is a flat member extending rearwardly from the bar and having upon its extended or free end trunnion-like members 32 and 33 which project, one upwardly and one downwardly, from its flat surface. At its other end, the lug 31 is provided 10 with an abrupt shoulder 34. Intermediate the ends of lug 31, and adjacent finger piece 30, a shoulder 34^a formed.

When my improved door fastener is not in use, it will normally be turned downwardly to the 15 dotted line position shown in Fig. 1, or as shown in Fig. 5, where it does not extend across the opening edge of the door. When, however, it is desired to place it into operative position, the bar is grasped and turned from the dotted line position to the full line position in Fig. 1, the pivot or stud 23 turning in the plate 26 to permit this movement. It is turned to a position wherein the trunnions or pins 32 and 33 will enter the enlarged end 15 of the slot 14 in the fitting 12. It 20 will be apparent that the members 32 and 33 will only enter this slot when the lug 31 is slightly above the longitudinal portion of the slot 14.

After the trunnions have been inserted through the portion 15 of the slot, as described above, the 30 bar 29 is dropped slightly about its pivot pin 23 so that the lug 31 registers with the slot 14. It will be apparent that in this position the member 33 will extend below the lower edge of the slot 14 so as to prevent the bar from being disengaged from the fitting on the door.

The door fastener is now in operative position, as shown in Fig. 2. If the door is now opened, the 40 bar 29 will be swung about its pivot 28 to the position shown in Fig. 3. At the same time, the lug 31 will be moved through the slot 14 from the left-hand end to the right-hand end thereof, as shown in the drawings, until the abrupt shoulder 34 engages and brings up against the right-hand edge of the enlarged portion 16 of the slot 14. This 45 engagement of the shoulder 34 with the edge of the slot not only prevents further movement of the door, but prevents the pins or trunnions 32 and 33 from moving into the enlarged portion 16 of the slot and possibly moving to a position where 50 the bar might become disengaged from the door. If it is desired to have the door remain open, a slight downward movement of the bar 29 will bring shoulder 34^a into engagement with the step 16^a, and latch the door in open position.

55 When the door is closed, the member 29 will of course move from the position shown in Fig. 3 to the position shown in Fig. 2, and it will be seen that it is only when the door is fully closed that the members 32 and 33 will again register 60 with the enlarged end 15 of the slot so that they may be disengaged therefrom. At this time it will be necessary to move the member 31 upwardly to a slight extent past the beveled shoulder 19 to release the trunnion 33 from the lower wall 65 of the enlarged portion 15 of the slot, for it will be seen that as long as the member 31 is in the slot 14, the member 33 cannot be released. This upward movement necessary for release is not possible until the member 31 reaches the beveled 70 portion 19, which, as shown in Fig. 2, will not take place until the door is fully closed. The member 31 is relatively wide in order to effect this result.

This is an important feature of the operation of the device from the standpoint of safety in that it can never be disengaged from the door until the latter is completely closed.

By providing the enlarged ends 15 and 16 at 5 each side of the slot 14, I construct the device so that it may be mounted upon right- or left-hand doors, as desired. As shown in the drawings, the left-hand slot 15 only is used, while if the door were hinged at the other side, the 10 right-hand slot 16 would be used. As the bar 29 and its associated parts are entirely symmetrical, these parts may simply be turned end 15 for end if mounted on a door swinging in the other direction. The beveled corners 19 between the slot 14 and the enlarged ends of this slot permit the lug 31 to ride easily from the enlarged ends into the longitudinal portion 14 if 20 for any reason the lug happens to be out of alignment with this slot.

It will also be seen that as the member 29 is of arcuate shape, it will at all times clear the edge of the door, as shown in Figs. 2 and 3, and will not engage with and mar the latter when the 25 door is opened.

The bar 29, as shown in Fig. 5, has a stop member 29^a adapted to strike a portion of the plate or fitting 20 or the screw 21 securing plate 20 to the door jamb, as shown in Fig. 5, and will prevent the lug 31 and trunnions 32 and 33 from 30 striking the door jamb and marring the same.

The present application is a continuation in 35 part of my copending application, Serial No. 1 752,295, filed November 9, 1934.

While I have shown and described a preferred 40 embodiment of my invention, it will be understood that it is not to be limited to all of the details shown, but is capable of modification and variation within the spirit of the invention and within the scope of the appended claims.

What I claim is:

1. A door fastener comprising a fitting adapted 45 to be secured to the door jamb, a slotted plate adapted to be secured to the door, a rigid bar pivotally secured to said jamb fitting at one end and having on the other end a member slidably received in said slot, said slot having enlarged 50 portions at each end to permit the insertion and withdrawal of said member, projecting means on said member within the slot adapted to engage the walls of the slot, said projecting means being insertable and withdrawable through said enlarged portions, and said member having a portion adapted to engage one end of the slot and prevent said projecting means registering with 55 the enlarged portion at that end.

2. A door fastener comprising a fitting adapted 60 to be secured to the door jamb, a slotted plate adapted to be secured to the door, a rigid bar pivotally secured to said jamb fitting at one end and having on the other end a member slidably received in said slot, projecting means on said member within the slot adapted to engage the side edges of the slot and prevent disengagement 65 of said member, said slot having enlarged portions at both ends to permit said projecting means to pass therethrough, and said member having a portion adapted to engage one end of the slot to prevent said projecting means reaching the enlarged portion at that end.

EDWARD R. SARGENT.
